Primary Examiner — Jae Liang(74) *Attorney, Agent, or Firm* — Andrus Intellectual Property Law, LLP(57) **CLAIM**

The ornamental design for a homogenizer as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front top perspective view of a homogenizer according to the design;

FIG. 2 is another front top perspective view thereof;

FIG. 3 is a rear top perspective view thereof;

FIG. 4 is a right top perspective view thereof;

FIG. 5 is another right top perspective view thereof; and,

FIG. 6 is a left top perspective view thereof.

The bottom side of the homogenizer does not form part of the claimed design. The broken lines represent the bounds of the claimed design; the broken lines form no part of the claimed design.

1 Claim, 6 Drawing Sheets
